FIG. 1 is a rear perspective view of a foldable wagon according to the new design.

FIG. 2 is a front view of the foldable wagon shown in FIG. 1.

FIG. 3 is a rear view of the foldable wagon shown in FIG. 1.

FIG. 4 is a right side view of the foldable wagon shown in FIG. 1.

FIG. 5 is a left side view of the foldable wagon shown in FIG. 1.

FIG. 6 is a top view of the foldable wagon shown in FIG. 1; and,

FIG. 7 is a bottom view of the foldable wagon shown in FIG. 1.

The broken lines in the drawings illustrate portions of the foldable wagon that form no part of the claimed design.
